CLAIM

The ornamental design for a digital camera, as shown and described.

DESCRIPTION

FIG. 1 is a Front view of a digital camera showing our new design;

FIG. 2 is a Back view thereof;

FIG. 3 is a Top view thereof;

FIG. 4 is a Bottom view thereof;

FIG. 5 is a Left view thereof;

FIG. 6 is a Right view thereof;

FIG. 7 is a Front Perspective view thereof; and,

FIG. 8 is a Front Perspective view thereof from a different angle than FIG. 7.

The broken lines show portions of the digital camera that form no part of the claimed design.

1 Claim, 8 Drawing Sheets---
